(57) **CLAIM**

The ornamental design for a foot cuff for therapeutic compression of a foot, as shown and described.

DESCRIPTION

FIG. 1 is a bottom plan view of a first embodiment of a foot cuff for therapeutic compression of a foot showing our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view of a second embodiment of a foot cuff for therapeutic compression of a foot showing our new design; and,

FIG. 8 is a top plan view thereof.

The broken lines in the drawings indicate environmental structure, which forms no part of the claimed design.
